UNITED STATES PATENT OFFICE.

GUILIO S. GUADAGNI, OF PROVIDENCE, RHODE ISLAND.

DEPOSITING MACHINE.

Application filed July 18, 1922. Serial No. 575,895.

To all whom it may concern.

Be it known that I, GUILIO S. GUADAGNI, a subject of the King of Italy, residing at Providence, in the county of Providence and State of Rhode Island, have invented certain new and useful Improvements in Depositing Machines, of which the following is a specification.

My invention relates to machines for depositing cordials in confections.

The essential objects of my invention are to successfully deliver a thin liquid, such as a cordial, to the molds; to effectively control the delivery at all times; to deliver without breaking the mold; to maintain the liquid supply at a proper degree of temperature; to prevent graining of the cordial; and to enable substitution of parts.

To the above ends primarily, but not exclusively, my invention consists in such parts and in such combinations of parts as fall within the scope of the appended claims.

In the accompanying drawings which form a part of this specification,

Figure 1 is a side elevation of a machine embodying my invention,

Figures 2 and 3, partial front and rear end views respectively of the same,

Figure 4, a fragmentary side elevation of the machine adjacent the tank,

Figure 5, a section on line 5—5 of Figure 1,

Figures 6 and 7, sections of the tank on line 6—6 of Figure 3, showing the parts in different positions,

Figure 8, a plan of the trough plate, and

Figure 9, a section of the same on line 9—9 of Figure 8.

Like reference characters indicate like parts throughout the views.

The framework of my machine may be of any construction best suited to carry the operating parts. In the form thereof herein shown it comprises four uprights 15, cross pieces 16 and braces 17. Fastened to the tops of each pair of uprights, extending longitudinally of the frame, by bolts 19 or otherwise are rails 20, constituting a track. Fast to the uprights below the rails 20 is a table 21 consisting of end angle bars 22 and side angle bars 23 adapted to support and guide a tray 25 for containing the confection mould to be filled. 24 is a guide strip fast to one of the bars 23.

55 A flaring or downwardly tapering metal

tank 26 has hollow side walls 28 and hollow end walls 30. The double walls 28 and 30 are integral and therefore continuous so as to form a chamber or jacket 32 for water entirely around the tank. The top of each 60 wall 30 is provided with a hole 34 for the admission of water. The walls 28 and 30 are at their lower ends compressed and outwardly to form a peripheral flange 36. The floor of the tank consists of a metallic 65 detachable strip 38 provided with marginal holes 40 adapted to receive screws 41 which pass through holes 42 in the flange 36. The strip or floor is thus readily detachable. At 70 regular intervals longitudinally of the strip 70 are depending spouts 47.

Fast to the outer face of the upper portions of each end wall 30 of the tank is a pair of brackets 48 carrying pintles 50 upon which are mounted rolls 52 provided with 75 peripheral grooves 53 in which register the rails 20. The tank is manually caused to slide or travel on the rails by means of a pair of horizontal handles 55 fastened to one of the walls 28 and projecting laterally 80 from the top thereof. Fastened by hooks or straps 57 to the opposite side wall 28 of the tank is a gas pipe or jet 58 provided with a longitudinal series of perforations 59 and having in this instance a reduced projecting 85 end portion 60 fast to which is a flexible gas tube 62 communicating with any convenient source of heat supply, and supported intermediate its length by a guide roll 64 mounted on a pintle 65 in a sheave or bracket 90 67 fast to one of the rails 20.

Attached to the bottom of the tank is an oblong discharge plate 69, having in its upper face a series of recesses or troughs 71 extending transversely from an intermediate 95 portion of the plate to one side thereof, and spaced from each other in such a manner as to severally correspond with the spouts 47. Compressible disks 73, preferably of rubber, are seated in the troughs 100 immediately in alignment with the spouts. At each side of its center the plate 69 is cut away, as at 75, but this is not essential. The resultant laterally extending portions 76 constitute the rear margin of the plate 105 69 whose lateral edges are in substantial alignment with the corresponding edges of the plate or floor 38. There are curved pins or hooks 79 upon intermediate portions of the ends of the member 69 to which are at- 110

tached the ends of helical springs 81 whose upper ends are attached to pins or hooks 83 fast to the walls 30 above. In the forward portion of the member 69 is a hook or pin 85 to which is attached a helical spring 86 having its upper end attached to a hook or pin 88 fast to the front wall of the tank. Operating handles are fastened to the plate 69 at its forward edge comprising a horizontal portion 89 and an upwardly inclined portion 90.

The hollow character of the tank walls admits the introduction of water and this is maintained at any required temperature 15 during the depositing operation in order to prevent graining of the cordial or depositing liquid. The mold with its parallel transverse rows of cavities for forming the candies is contained in the tray 25 and the 20 latter is pushed longitudinally of the table in contact with the guide strip 24 to a suitable position. The horizontal handles of the tank are next seized and the tank is pushed to a position in vertical alignment with the 25 rearmost row of cavities. The handle attached to the discharge plate 69 is now manually depressed and this movement opens the spouts and the liquid passes through the troughs 71 into the several cavities of the mold below. When this row has 30 been filled the handle is released and the several springs return the plate 69 to closed position to cut off the flow. The tank is next moved to a point above the next adjacent 35 row of cavities and the described operations are repeated. The disks 73 insure an unbreakable closure of the spouts.

It will be noted that the discharge of the liquid by the troughs is at an incline to the 40 mold and therefore breakage of the mold is prevented, particularly when the mold is of starch.

I claim:—

1. In a machine of the character described, a track, a supply tank slidably mounted on the track, a tiltable plate supported by the tank provided with a series of troughs, a series of spouts carried by the tank registering in the troughs, and means for moving the plate. 45
2. In a machine of the character described, a track, a supply tank, depending spouts in the bottom of the tank, and a plate pivotally supported by the tank provided with troughs in which the spouts register. 50
3. In a machine of the character described, a track, a supply tank mounted on the track comprising walls and a floor detachably engaged by the walls, spouts in the floor, a plate bodily tiltably supported by the trough 60 provided with transversely disposed troughs open at one end, and disks in the troughs engageable by the spouts. 65
4. In a machine of the character described, a supply tank having a multiplicity of discharge spouts, a plate common to all of the spouts and bodily movably mounted, and a multiplicity of troughs movable with said plate and open at one end, said troughs serving as cut-off means for said spouts when in 70 one position.
5. In a machine of the character described, a supply tank having a multiplicity of discharge spouts, a plate common to all of the spouts and bodily movably mounted, a multiplicity of troughs movable with said plate and open at one end, said troughs serving as cut-off means for said spouts when in one position, and means to move said plate to incline the troughs for the discharge of the 80 liquid from said tank. 75

In testimony whereof I have affixed my signature.

GUILIO S. GUADAGNI.
